UNITED STATES PATENT OFFICE

2,641,451

HEAT EXCHANGER

Edward W. Kaiser, Chicago, Ill.

Application November 4, 1950, Serial No. 194,173

4 Claims. (Cl. 257—199)

1

This invention relates, generally, to heat exchangers, and it has particular relation to such devices for maintaining a liquid in a tank and in a pipe connected thereto at an elevated temperature so as to maintain the contents thereof in the liquid state, which contents would be solid or viscous at room temperature.

Among the objects of this invention are: To circulate a heated fluid, such as steam or hot water, around the pipe through which the liquid flows from or to the tank in order to maintain not only such liquid but also the liquid in the tank at the elevated temperature; to direct the flow of the heated fluid so that it follows a circuitous path; to provide a relatively great surface within the tank in contact with the liquid therein on the one hand and maintained at the elevated temperature on the other hand; to prevent intermingling between the liquid in the tank and pipe and the heated fluid; and to connect such a heat exchanger either to a jacketed or non-jacketed piping system.

Other objects of this invention will, in part, be obvious and in part appear hereinafter.

This invention is disclosed in the embodiments thereof shown in the accompanying drawings and it comprises the features of construction, combination of elements and arrangement of parts which will be exemplified in the constructions hereinafter set forth and the scope of the application of which will be indicated in the appended claims.

For a more complete understanding of the nature and scope of this invention, reference can be had to the following detailed description, taken together with the accompanying drawings, in which:

Figure 1 is a view, partly in side elevation and partly in section, illustrating one heat exchanger constructed in accordance with this invention and applied to a tank the contents of which are to be maintained in the liquid state;

Figure 2 is a view, similar to Figure 1, showing a modified form of the heat exchanger and how it can be adapted to be connected to a jacketed conduit system such as that disclosed in my co-pending application Serial No. 47,851, filed September 4, 1948;

Figure 3 is a detail sectional view taken generally along the line 3—3 of Figure 2;

Figure 4 is a view, similar to Figure 2, illustrating how the heat exchanger of the present invention can be connected to a non-jacketed system.

Referring now particularly to Figure 1 of the drawings, it will be observed that the reference character 10 designates, generally, a tank, only

2

a portion of which is shown, that may be adapted for receiving a liquid, such as wax, which is solid at room temperature and must be maintained at an elevated temperature in order to keep it in the liquid state. It will be understood that other materials which are similar in nature to wax may be received and heated in the tank 10. It is contemplated that viscous materials also may be used and that they are of such nature that they must be maintained at an elevated temperature in order to permit them to flow readily into or out of the tank 10. One of the tank walls is indicated at 11 and it interfits with a shell 12 which may be cylindrical. The wall 11 and shell 12 may be secured together in liquid tight relation by any suitable means such as by welding 13.

In accordance with this invention the means employed for maintaining the liquid in the tank 10 in the liquid state is also employed for maintaining the liquid in the inlet or outlet pipe to the tank 10 in the liquid state. For this purpose a tank nipple 14 is employed and, as shown, it comprises a short length of pipe which extends through a suitable aperture in the wall 11 for a short distance. The tank nipple 14 is secured in fluid tight relation to the wall 11 by welding 15. The outer end of the tank nipple 14 is secured by welding 16 to a radially extending flange 17. The tank nipple 14 and flange 17, when arranged as described, constitute an integral part of the tank wall 11. The remaining parts of the heat exchanger constructed in accordance with this invention are readily removable from the tank 10 in a manner which will be apparent presently.

In order to flow the liquid into or out of the tank 10 an inner pipe 20 is employed. The pipe 20, as illustrated, is formed of metal, such as stainless steel, steel, or the like. At its inner end it opens into the tank 10 and is below the surface of the liquid therein. The inner pipe 20 extends centrally of the tank nipple 14 and is held in spaced relation by means which will be described presently.

Surrounding the inner pipe 20 and extending a substantial distance into the tank 10 is an outer pipe 21. This pipe, like the inner pipe 20, is formed of metal such as stainless steel, steel or the like. It has a large surface which contacts the liquid in the tank 10 and thus provides an excellent heat transfer medium for a heated fluid which is circulated through it. Since the outer pipe 21 and the inner pipe 20 project into the tank 10 a substantial distance it is desirable to provide a support therefor near the inner ends thereof. For this purpose a pedestal 22 is em-

ployed. With a view to enclosing the inner end of the outer pipe 21 an annular plate 23 is employed. As indicated at 24 the plate 23 is welded to the outer surface of the inner pipe 20. The periphery of the plate 23 is welded by suitable means to the inner end of the outer pipe 21. The construction thus described provides an annular space 25 within the outer pipe 21 and around the inner pipe 20 through which a heated fluid, such as steam, can be circulated for the purpose not only of heating the liquid in the tank 10 but also for maintaining the liquid within the inner pipe 20 in the liquid state so that it will flow freely therethrough.

The outer pipe 21 extends centrally through the tank nipple 14 and through the flange 17 welded thereto. By means of welding 26 the outer pipe 21 is secured to a flange 27 which abuts the flange 17 and to which it is secured by suitable through bolts (not shown). It will be understood that a suitable gasket may be provided between the flanges 17 and 27 and between similar flanges described hereinafter in order to provide a fluid tight construction. It will be understood that the flange 27 welded at 26 to the outer pipe 21 constitutes closure means for the outer end of the tank nipple 14 and between it and the outer pipe 21. This also constitutes a mechanical support for the outer end of the outer pipe 21.

At its extreme outer end the outer pipe 21 is secured by welding 28 to a radial flange 29. Where the inner pipe 20 is not arranged to extend into a jacketed conduit system, means are provided here for making a sealed connection between the inner pipe 20 and the outer pipe 21. For this purpose the flange 29 is secured, as by bolts, to another flange 30 which forms a part of a stuffing box that is indicated, generally, at 31. The flange 30 and stuffing box 31 constitute closure means between the outer end of the outer pipe 21 and the portion of the inner pipe 20 that extends centrally therethrough.

As indicated hereinbefore the space 25 between the inner pipe 20 and the outer pipe 21 is arranged to be filled with a heated fluid. For this purpose an inlet conduit 32 and an outlet conduit 33 are connected to the outer pipe 21 between the flanges 27 and 29 as illustrated. Steam is caused to flow through the conduits 32 and 33 in the direction indicated by the arrows for circulating the heated fluid through the space 25 to heat the liquid in the tank 10 and also to maintain the liquid within the inner pipe 20 in the liquid state.

It will be understood that a heated fluid, such as steam, will completely fill the space 25. Under proper conditions heat will be extracted from the steam within the space 25 and it will condense so that the condensate will flow out through the conduit 33.

In Figure 2 of the drawings, a heat exchanger constructed generally similar to that shown in Figure 1 and described above is illustrated. In order to improve the circulation of the heated fluid between the inner pipe 20 and the outer pipe 21 in the space 25, there is provided an intermediate pipe 36. It will be observed that the intermediate pipe 36 is located between the inner pipe 20 and the outer pipe 21 and is concentric therewith. The intermediate pipe 36 projects through the outer end of the outer pipe 21 and through the nipple 14' which, in this instance, is provided with threads 16' for receiving the flange 17. The intermediate pipe 36 is secured by welding 37 to a flange 30' which, as de-

scribed hereinbefore, may be secured to the flange 29 by suitable bolts. The flange 30' constitutes a closure means between the outer pipe 21 and the intermediate pipe 36. It will be observed that the inner end of the intermediate pipe 36 is spaced, as indicated at 38, from the extreme inner end of the outer pipe 21 or the plate 23. The space 38 permits the circulation of the heated fluid from the inside of the intermediate pipe 36 where it is in intimate contact with the outside of the inner pipe 20 to the outside thereof and in intimate contact with the inner surface of the outer pipe 21. It is noted here that the plate 23 is secured about its outer periphery by welding 24' to the inner end of the outer pipe 21. Also it will be noted that the flange 29 is secured by threads 28' onto the outer end of the outer pipe 21.

At its extreme outer end the intermediate pipe 36 is secured by welding 39 to a flange 40. It is desirable to seal off the space between the outer end of the intermediate pipe 36 and the outer surface of the inner pipe 20. For this purpose a plate 41 is employed. As shown more clearly in Figure 3 the plate 41 has a relatively close fit with the outer surface of the inner pipe 20 although preferably it is not securely attached thereto. The sliding fit thus provided serves to contain the heated fluid which is circulated through the inlet and outlet conduits 32 and 33 to the intermediate pipe 36. It is here noted that the inlet conduit 32 is connected to the intermediate pipe 36 while the outlet conduit 33 remains connected to the outer pipe 21. Thus the heated fluid flows into the intermediate pipe 36 and around the exterior of the inner pipe 20. It flows through the space 38 and into the portion of the space 25 outside of the intermediate pipe 36 and thence to the outlet conduit 33.

It will be noted that the plate 41, which is apertured centrally to receive the inner pipe 20, is clamped between the flange 40 and a flange 42 that is secured by welding 43 to one end of a jacket 44. The jacket 44 constitutes a part of a jacketed conduit system the details of which are set forth more completely in the copending application above referred to. For present purposes it is merely pointed out that the jacket 44 is spaced from the inner pipe 20 so as to provide an annular space 45 therearound through which a heated fluid, such as steam or hot water, can be circulated for maintaining the liquid within the inner pipe 20 in the liquid state. A conduit 46 may be connected to the jacket 44 to form a part of the heated fluid circulating system. The heat exchanger illustrated in Figure 4 is generally similar to that illustrated in Figure 2 and described above. It differs in that the threaded connections 16' and 28' are not employed and welding is substituted therefor. Another distinction is that the stuffing box 31 described above in connection with Figure 1 is employed, since the inner pipe 20 in this modification does not extend into a jacketed conduit system.

In the heat exchangers shown in Figures 1, 2 and 4 the inner pipe 20 is anchored by the plate 23 to the adjacent inner end of the outer pipe 21. The outer end of the outer pipe 21 is anchored through the flanges 27 and 17 and the pipe nipple 14 or 14' to the wall 11. Thus the outer pipe 21 expands inwardly of the tank 10 and carries with it the inner pipe 20. The latter is free to move at its outer end since it extends through the stuffing box 31 or the plate 41 through each of which it is slidably.

When the intermediate pipe 36 is employed, as shown in Figures 2 and 4 to provide a counterflow of the heating medium through the outer pipe 21 and around the inner pipe 20, the intermediate pipe 36 is anchored at its outer end to the wall 11 while its inner end is free to expand inwardly of the tank 10. This construction permits independent expansion and contraction of the pipes 20, 21 and 36 on change in temperature while maintaining fluid tight the connections therebetween and with the tank 10. The heating medium from the inlet pipe 32 first contacts the inner pipe 20 and, while flowing through the intermediate pipe 36, transfers some of the heat in it to the liquid in the inner pipe 20. During its counterflow between the intermediate pipe 36 and the outer pipe 21 additional heat is removed from the heating medium and is transferred to the surrounding liquid in the tank 10.

Since certain further changes can be made in the foregoing constructions and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. For combination with a tank containing a liquid to be maintained at an elevated temperature, a tank nipple for connection to a wall of the tank, an inner pipe extending through said tank nipple and opening into the tank through which the liquid therein can flow, an outer pipe extending through and having sealed connection to said tank nipple and surrounding and spaced from said inner pipe, an intermediate pipe extending into and having sealed connection to said outer pipe outside of said tank nipple, said intermediate pipe being spaced from said inner and outer pipes and constituting a baffle in the space therebetween, closure means within the tank between said outer and inner pipes, closure means without said tank between said intermediate and inner pipes, and conduit means connected to said outer and intermediate pipes without the tank for circulating through said space between said inner and outer pipes as directed by said baffle a heated fluid for maintaining the liquid in the tank and in said inner pipe at the elevated temperature.

2. For combination with a tank containing a liquid to be maintained at an elevated temperature, a tank nipple for connection to a wall of the tank, an inner pipe extending through said tank nipple into the tank for a substantial distance and opening into the same through which the liquid therein can flow, an outer pipe having sealed connection to and extending through said tank nipple and into said tank where a substantial portion of its outer surface contacts the liquid therein, said outer pipe surrounding and spaced from said inner pipe, an intermediate pipe extending into and having sealed connection to said outer pipe outside of said tank nipple, said intermediate pipe being spaced from said inner and outer pipes and constituting a baffle in the space therebetween, closure means within the tank between said outer and inner pipes, closure means without said tank between said intermediate and inner pipes, and conduit means connected to said outer and intermediate pipes without the tank for circulating through said space between said inner and outer pipes as directed by said baffle a heated fluid for maintaining the liquid in the tank

the tank and in said inner pipe at the elevated temperature.

3. For combination with a tank containing a liquid to be maintained at an elevated temperature, a tank nipple for connection to and extending through a wall of the tank, an inner pipe extending centrally through said tank nipple into the tank for a substantial distance and opening into the same through which the liquid therein can flow, an outer pipe spaced centrally from and having sealed connection to said tank nipple and extending into said tank where a substantial portion of its outer surface contacts the liquid therein, said outer pipe surrounding and spaced from said inner pipe, an intermediate pipe extending into and having sealed connection to said outer pipe outside of said tank nipple, said intermediate pipe being spaced from said inner and outer pipes and constituting a baffle in the space therebetween, closure means within the tank between said outer and inner pipes, closure means without said tank between said intermediate and inner pipes, and conduit means connected to said outer and intermediate pipes without the tank for circulating through said space between said inner and outer pipes as directed by said baffle a heated fluid for maintaining the liquid in the tank and in said inner pipe at the elevated temperature.

4. For combination with a tank containing a liquid to be maintained at an elevated temperature, a tank nipple for connection to a wall of the tank, an inner pipe extending through said tank nipple and opening into the tank through which the liquid therein can flow, an outer pipe extending through and having sealed connection to said tank nipple and surrounding and spaced from said inner pipe, an intermediate pipe extending into and having sealed connection to said outer pipe outside of said tank nipple, said intermediate pipe being spaced from said inner and outer pipes and constituting a baffle in the space therebetween, closure means within the tank between said outer and inner pipes, closure means without said tank between said intermediate and inner pipes, conduit means connected to said outer and intermediate pipes without the tank for circulating through said space between said inner and outer pipes as directed by said baffle a heated fluid for maintaining the liquid in the tank and in said inner pipe at the elevated temperature, a jacket surrounding and spaced from said inner pipe and extending from said closure means between said intermediate and inner pipes, and conduit means connected to said jacket for circulating through the space between it and said inner pipe a heated fluid for maintaining the liquid in said inner pipe at an elevated temperature.

EDWARD W. KAISER.
